UNITED STATES PATENT OFFICE

2,445,923

FUEL INJECTION DEVICE FOR INTERNAL-COMBUSTION ENGINES

Edward Philip Paxman, Colchester, England

Application June 26, 1944, Serial No. 542,176
In Great Britain April 22, 1943

3 Claims. (Cl. 137—53)

1

This invention relates to fuel injection devices and while having more particular reference to the fuel injection devices of certain types of internal combustion engines is also applicable to injection devices of the kind used in boiler and other furnaces.

The object of the invention is to provide an improved form of valve device applicable to a fuel injector nozzle to enable the construction and manufacture of such nozzles to be considerably simplified.

According to the invention a fuel injection device is provided wherein the fuel is admitted through a nozzle with which co-operates a valve component comprising a compressible body capable of being initially set so that the pressure of the injected fuel is utilized in lifting the valve off of its seat.

According to the preferred form of the invention the improved fuel injection device comprises a casing, means for securing said casing in position adjacent a combustion chamber or the like, a valve component in said casing formed of a compressible plastic or other resilient material adapted to engage a fixed valve seating and to open under pressure due to the incoming fuel and means for setting the pressure at which said valve will open.

Reference will now be made to the accompanying drawings in which:

Fig. 1 is a sectional elevation showing one form of the improved fuel injector nozzle, and

Fig. 2 is a sectional elevation of an alternative form of construction.

Referring first to Figure 1, a fuel injector nozzle for an internal combustion engine comprises a protective casing or sleeve *a* of substantially cylindrical form which is screw threaded at its forward end *b* to enable it to be mounted in a cylinder head *c* in a manner similar to a sparking plug. Within the casing *a* is mounted an inlet valve element *d* which is made of a resilient material such as a plastic material of a character capable of being compressed but possessing also a degree of recovery which enables it to act in a manner similar to a spring. The valve element *d* is of cylindrical form having a substantially conical tip *e* at its end nearer the combustion chamber *f*, this tip being formed of a heat-resistant hardened steel and being secured to the valve element by means of a rearwardly extending shank *e'* fitted into a cylindrical socket in the valve element.

The outer end of the valve element is of enlarged diameter at *g* to form an annular shoulder

2

h which abuts an annular shoulder *i* formed within the casing *a*. The outer end of the valve element has a central passage *j* communicating with radial ports *k* situated slightly in advance of the annular shoulder *h* and communicating with an annular passage *l* formed between the valve element *d* and the inner wall of the casing *a*. The casing *a* has a central aperture *m* at its inner end forming a valve seat in which the steel tip *e* of the valve element engages, being held in this position with its annular shoulder *h* engaging the shoulder *i* by the flanged end *n* of an inlet pipe *o*. This mounting of the valve element enables it to be initially compressed to such a degree that it exerts pressure on the valve seat *m* equal to the pressure at which the valve should open during operation.

The delivery pipe *o* is enabled by the construction above described to enter the device in a position co-axial with the nozzle and this pipe is secured in position by a nut *q* which engages a screw-threaded socket in the casing member *a* which may be provided externally with a hexagonal portion *p* to facilitate its mounting in the cylinder head *c*. The inner end of the nut *q* bears against the flanged end *n* of the inlet pipe and the pressure necessary to seat the member *e* on the valve seat *m* is obtained by screwing in the nut *q*. If, for example, it is intended that the valve should open at a pressure of 1500 lbs. per square inch, the valve element *d* should be compressed so that it exerts a force on its seating *m* equal to that which would be created by pressure due to the incoming fuel delivered by the pump and acting on the inner end *e* of the valve element. It is thus necessary for the valve element to be capable of being compressed still further to open and allow fuel to enter the combustion chamber.

In the alternative construction shown in Fig. 2, the interior of the fuel injector is constructed and arranged in the same manner as already described with reference to Fig. 1 and the component parts are indicated by the same reference letters, but the casing *a*, in this instance also contains a cylindrical steel nozzle *r* which provides at its inner end the valve seating *m* and at its outer end bears against the shoulder *h* on the valve member. In this form of the invention the casing *a* is formed with cooling fins *s* which may be of hexagonal form to facilitate screwing of the casing *a* into the operative position shown.

For the purpose of making a joint between casing *a* and the cylinder head *c* capable of resisting the pressure of the gases in the combus-

tion chamber, it is preferred to employ a washer, which may be of copper, indicated at *v* in Figs. 1 and 2, which is interposed between the inner end of the nozzle and the end of the recess in which it is mounted. In Fig. 2 there is also shown a protective button *t* formed of a heat-resisting material to screen the face of the nozzle from the effects of combustion and the gases resulting therefrom.

By employing a valve element made of a plastic or other compressible material, the invention enables manufacture to be considerably cheapened and it is especially applicable to small engines as it eliminates the use of a spring and complex port arrangements frequently found in nozzles of the kind described. The construction also enables the fuel delivery connection to be made coaxial with the nozzle.

I claim:

1. A fuel injection device for an internal combustion engine of the compression-ignition type, comprising a casing, a valve seat formed centrally at the inner end of said casing, a valve component mounted within said casing providing a surrounding annular passage between it and the casing and comprising a substantially cylindrical member composed of solid compressible material, a conical tip composed of heat-resistant material carried by the inner end of said valve component and adapted to engage said seat, a fuel delivery pipe secured to said casing in axial alignment with said valve component, a central inlet passage and radial ports in said valve component through which fuel from said delivery pipe passes to said annular passage and said valve seat, and means for exerting pressure on the outer end of said valve component through said delivery pipe, the tip having an effective area exposed to hydraulic pressure in said annular passage which is larger than the area of said central inlet passage, and the valve component being inherently compressible axially by hydraulic pressure in said annular passage acting on said effective area of the tip to disengage the tip of the valve component from the valve seat.

2. A fuel injection valve comprising a casing having a seat therein, a valve component composed of a solid compressible plastic material and embodying an elongated stem having a tip at one end composed of a hardened heat-resistant metal engageable with the seat in the casing and having a central axial fuel inlet passage in its other end, said stem being spaced from the casing to form an annular passage which communicates with the seat in the casing and said fuel inlet passage in the valve component, a fuel delivery pipe disposed coaxially with the valve component and communicating with said fuel inlet passage therein, and means for applying a variable pressure to the fuel delivery pipe to compress axially the stem of the valve component and

thereby press the tip of said stem against the seat in the casing, the tip having an effective area exposed to hydraulic pressure in said annular passage which is larger than the area of said central inlet passage, and the valve component being inherently compressible axially by hydraulic pressure in said annular passage acting on said effective area of the tip of the stem of the valve component to disengage the tip of the valve component from the valve seat.

3. A fuel injection device for an internal combustion engine of the compression-ignition type, comprising a casing having a valve seat formed centrally at its inner end and an annular shoulder axially spaced outwardly therefrom, a valve component composed of a solid compressible plastic material and embodying an elongated stem having at one end a tip composed of hardened heat-resistant steel engageable with the valve seat and having an annular enlargement at its other end engageable with said annular shoulder of the casing, said stem of the valve component being spaced radially from the casing to form a surrounding annular passage which communicates with the valve seat, and the valve component having a central axially extending inlet passage extending inwardly from its outer end and through said annular enlargement and having radial ports connecting said central passage and surrounding annular passage, a fuel delivery pipe in axial alignment with said valve component and engaging the outer end of said annular enlargement thereon, and means for applying a variable force to the fuel delivery pipe to compress axially and preload the valve component and thereby press the tip of the stem against the valve seat, the tip having an effective area exposed to hydraulic pressure in said annular passage which is larger than the area of said central inlet passage, and the valve component being inherently compressible axially by hydraulic pressure in said annular passage acting on said effective area of the tip to disengage the tip of the stem of the valve component from the valve seat.
